UNITED STATES PATENT OFFICE.

LLOYD DOUGLAS, OF MENLO PARK, CALIFORNIA.

PYROPHORIC LIGHTER.

Application filed February 18, 1928. Serial No. 255,333.

This invention relates to improvements in pyrophoric lighters of the pocket type in which is embodied novel means for making a spark and producing a flame.

5 An object of my invention is to provide a pocket size pyrophoric lighter wherein is compactly embodied novel means for producing a spark for the igniting of a wick.

Another object of my invention is to provide 10 a pyrophoric lighter having the various operating parts thereof compactly contained in a casing resembling a pen in shape.

Another object of my invention is to provide 15 a combined cigarette holder, pyrophoric lighter and pen, all being embodied in a convenient and compact form suitable for carrying in a vest pocket.

Another object of my invention is to provide 20 a combined pyrophoric lighter and cigarette holder, embodying a construction which permits the convenient use of the lighter without its detachment from the cigarette holder.

Other objects more or less apparent will 25 present themselves or will be specifically pointed out in the description to follow.

In the accompanying drawings illustrating the preferred form my invention may assume:

30 Fig. 1 is a side view of a pyrophoric lighter and cigarette holder embodying my invention;

Fig. 2 is a longitudinal sectional view of 35 my improved pyrophoric lighter taken on the line 2—2 of Fig. 4;

Fig. 3 is a sectional view taken on the line 3—3 of Fig. 2;

Fig. 4 is a sectional view taken on the line 4—4 of Fig. 2;

40 Fig. 5 is a sectional view taken on the line 5—5 of Fig. 2;

Fig. 6 is a sectional view taken on the line 6—6 of Fig. 2; and

Fig. 7 is a side elevation of my improved 45 pyrophoric lighter with a pen attached thereto, showing a part of the casing broken away and in cross section.

Referring to the drawings, the numeral 1 represents an oval shaped casing having a 50 detachable end piece 2 screwed into one end thereof and an enclosing end member 3 located at the other end. Attached to the end member 3, as by screws 4, is a circular shaped tubular member 5, which has one of its ends bent inwardly as at 6, and its oppo-

site end closed by a partition 7. An extension 8, which forms a part of the tubular member 5, is provided with a large opening 9 in its side. Movable located at the end of the extension 8 is a cap piece 10 which is 60 provided with a projecting part 11 that is movably located inside the said extension 8. The projecting part 11 is provided with a cut away part which forms an opening 12 of approximately the same size as the large 65 opening 9 in the tubular member 5. Secured to the end member 3 and to the partition 7, with its end extending beyond the latter, is a wick tube 13 which carries a wick 14. Also extending through the end 70 member 3 and the partition 7 is a tubular member 15 having one of its ends closed and a pyrophoric bar 16 projecting from and beyond its other end. A spiral spring 17 having one end bearing against the closed 75 end of the tubular member 15 and its other end pressing against the pyrophoric bar 16, serves to resiliently maintain the latter in an outwardly projecting position.

Movably extending through the partition 80 7 and a tubular projection 18 located on the latter, is a pin 19 having a square end 20 which extends through a steel disc 21 and the cap piece 10. A screw 22, with its head located on the outside of the cap piece 10, is 85 adapted to screw into the square end 20 of the pin 19, thereby providing suitable means for maintaining the steel disc 21 inside the cap piece. The pin 19 is formed with an enlarged central section which provides 90 shoulders that are located against the steel disc 21 and the partition 7. A spiral spring 23 encircles the circular projection 18 and is secured at one end to the end of pin 19 and at its opposite end to the wick tube 13. The 95 steel disc 21 is provided with a plurality of small teeth 24 which contact with the end of the pyrophoric bar 16 and are adapted to co-operate with the latter to produce a spark for the igniting of the end of the wick 14. 100

Movably mounted on the tubular member 5 and suitably held in position, as by projections 25, is a ring 26 which is provided with an inwardly extending projection 27 which passes through a slot located in the 105 side of the tubular member 5.

Movably located inside a tubular projection 28 which is secured to the partition 7, is a bar 29 which is provided adjacent the projection 27 with a pawl 30 and at its op- 110

posite end with a latch member 31 which is located inside and adjacent the end of the projecting part 11 of the cap piece 10. The latch member 31 is adapted to engage with a projection 32 located on the inside of the projecting part 11. A leaf spring 33, having its end pressing against the side of the pawl 30 tends to maintain the bar 29 in such a position that the latch member 31 is engaged 10 with the projection 32. The projection 27 secured to the ring 26 when the latter is turned is adapted to move the pawl 30 and turn the bar 29 so the latch member 31 may be released from the projection 32.

15 As shown in Fig. 1, the casing 1 is slidably located in a tube 34 and the same is adapted to be pulled outwardly to light a cigarette which may be inserted in the end of a cigarette holder 35, the latter being attached to the tube 34 by bands 36.

20 The end piece 2 may be substituted for a tubular extension 37 which is adapted to receive a pen or pencil 38.

25 As illustrated on the drawings the lighter is in a closed position with the openings 9 and 12 closed, and the spiral spring 23 in a wound up position. To produce a spark for the igniting of the wick 14 and to bring into registration the two large openings 9 and 12 30 respectively, in the extension 8 and projecting part 11, the ring 26 is turned by the hand so as to cause the extension 27 thereof to move the pawl 30. As the ring is turned and the pawl moved, the bar 29 is also turned and the latch member 31 is released 35 from the projection 32 of the projecting part 11. This then permits the pin 19, the cap piece 10, the steel disc 21 and the projecting part 11 to be turned by the spring 23 which is fastened at its ends to the pin 19 and to 40 the wick tube 13. As the spring 23 turns the said parts, the teeth 24 of the steel disc 21 contact with the end of the pyrophoric bar 16, thereby producing a spark for the ignition 45 of the wick 14. As the cap 10 and its projecting part 11 are turned, the opening 12 in the latter is brought around to a position where it coincides with the opening 9 in the extension 8 of the tubular member 5. 50 When the two openings are in this position the flame from the ignited wick 14 is allowed to pass therethrough for the lighting of a cigarette.

55 To close the openings 9 and 12, the cap piece 10 is turned in the opposite direction to a position which causes the projection 32 to engage with the latch member 31. The turning of the cap piece in this direction causes the spring 23 to again become con-

tracted preparatory to the next lighting operation.

60 It is obvious to those skilled in the art that my improved pyrophoric lighter may be embodied in other forms than the one shown and described herein, so for this and other reasons it is desired that my invention be included broadly within the spirit of the appended claims.

65 Having described my invention, what I claim is:

70 1. A pyrophoric lighter comprising a casing having a partition member located therein and an opening located adjacent an end thereof, a wick projecting through the partition member, a pyrophoric element projecting from the partition member adjacent the wick, a cap having an opening in its sides which is adapted to coincide with the opening in the casing, which said cap is pivotally attached by a pin to the partition member, a friction member secured to the cap and in contact with the pyrophoric element, and a spring attached at one of its ends to the pin for rotating the cap, the pin and the friction member, 75 whereby the friction member may be moved against the pyrophoric element to produce a spark for igniting the wick.

80 2. A pyrophoric lighter comprising a casing carrying a pyrophoric element and a wick, a cap pivotally attached by a pin to the casing, a friction member secured to the cap and in contact with the pyrophoric element, a spring attached to the pin which said spring may be compressed by turning 85 the cap, means engageable with the cap for maintaining the cap against rotation by the spring, and means for actuating the first mentioned means, whereby the cap and the friction member may be rotated by the 90 spring.

95 3. A pyrophoric lighter comprising a casing, a tubular member secured to the casing having an enclosing end member, a wick projecting beyond the end member, a pyrophoric element projecting from the end member at a point adjacent the wick, a cap carrying a friction member pivotally attached to the end member, the friction member being in contact with the pyrophoric element, and a spring connected to the cap and the tubular member for rotating the cap and the friction member, whereby the friction member may be moved against the pyrophoric element to produce a spark 105 for igniting the wick.

110 LLOYD DOUGLAS.
